UNITED STATES PATENT OFFICE.

BENJAMIN WEXLER, OF BROOKLYN, NEW YORK, ASSIGNOR TO THE PEELLE COMPANY,
OF BROOKLYN, NEW YORK, A CORPORATION OF NEW YORK.

LATCH FOR ELEVATOR-DOORS.

1,314,551.

Specification of Letters Patent.

Patented Sept. 2, 1919.

Application filed September 9, 1915. Serial No. 49,655.

To all whom it may concern:

Be it known that I, BENJAMIN WEXLER, a citizen of the United States, and a resident of New York city, borough of Brooklyn, in the county of Kings and State of New York, have invented certain new and useful Improvements in Latches for Elevator-Doors, of which the following is a specification.

This invention relates to certain new and useful improvements in latches for elevator doors and the object of my invention is to provide a new and improved latch or locking means for elevator shaft doors, which is thrown out of action at each door when the elevator car platform arrives at the level of the floor to which said latch pertains and which latch locks all doors in such manner that when the elevator car platform is not at the level of the floor to which the door pertains, the door cannot be opened to such an extent as to permit persons to fall through the opening into the shaft, but permits any door at any time, to be opened to such an extent that a person outside of the shaft and on any one of the floors through which the shaft passes, can extend an arm through the opening formed by the partly opened doors into the shaft to grasp the stopping and starting rope or like contrivance to start the car up or down, to the floor at which the said person stands, which attachment is simple in construction, strong and durable, can be applied on old elevators at well as on such just being constructed and installed and requires no change in the doors and can be applied on manually closed doors as well as on self closing doors.

In the accompanying drawings in which like letters of reference indicate like parts in all the figures:—

Figure 1 is an elevation of an elevator doorway having an upper and lower door section provided with my improved latch, the closed position of the doors being indicated in dotted lines.

Fig. 2 is a vertical sectional view of the same showing the elevator car with its platform at the level of the floor pertaining to said door.

Fig. 3 is a diagrammatic detail view of one construction of the latch.

Fig. 4 is a modification.

The door opening 1 leads to a loft or room having the floor 2 which is on the same level with the sill of said door opening. The

door opening can be closed by two vertically sliding door sections, an upper door section 3 and a lower door section 4, which sections are connected in the conventional way by ropes, cables or chains 5 passed over pulleys 6 secured to the vertical guides 7 on which the door sections slide. When the doors are so connected they move simultaneously and when the lower door is raised the upper door is lowered and when the upper door is raised the lower door is lowered. When the doors are equally balanced, they must be closed manually, that is to say either the upper door must be pulled downward or the lower door lifted, but in many cases the upper door is overweighted so that as soon as the doors are released from a suitable holding catch, they close automatically, as the upper door moves downward under its greater weight and thereby lifts the lower door section. The lower door section 4 is usually provided on its upper edge with a cross bar 8 which extends beyond the side edges of the lower door section and to the ends of which the cables, ropes or chains 5 are attached. To the side frame a latch lever 10 is pivoted at 11 in such a manner that its upper end can extend into the pathway of one end of the top cross bar 8 of the lower door section. In a construction adapted for doors which are not self closing, that is to say, if the upper door is not overweighted and thus the doors must be closed manually, the following construction is used.

The lower end of this latch lever 10 is provided with a longitudinal slot 12 into which a pin 13 passes from the upper end of a lever 14 likewise pivoted to the side frame at 15 and from the lower end of the lever 14 a head 16 projects which normally is in the vertical path of a cam piece 17 projecting from a hanger 18 projecting downward from the platform 19 of the elevator car, the hanger 18 and the head 16 on the lower end of the lever 14 being so positioned that when the elevator car platform is in alignment with the floor 2, the cam 17, acting on the head 16 forces the lower end of the lever 14 to the right whereby the upper end of the lever 14 is moved to the left and in turn swings the upper end of the lever 10 to the right and out of the path of the projecting end of the descending cross bar 8, so that the doors

can now be opened and the cross bar 8 moved downward, as is necessary in so opening the doors. The latch levers 14 and 10 are held in these positions as long as 5 the cam 17 on the hanger 18 of the car platform bears against the head 16 and holds the same pressed to the right against the tension of the spring 20. As soon as 10 the car moves upward or downward from the floor, the cam 17 releases the head 16 permitting the spring 20 to force the lower end of the lever to the left, that is toward the elevator shaft, thus automatically bringing the lever 10 into locking position. 15 If accidentally the doors have not been closed when the car begins to move up or down and the cross bar 8 is below the upper end of the latch lever 10, the doors can be closed nevertheless, as the rising cross bar 20 8 striking the inner edge of the latch lever 10 pushes the same to one side until the cross bar 8 has passed above the upper end of the latch lever. When the bar 8 passes the upper end of the latch lever 10, 25 the same snaps outward under the action of the spring 20 and thus prevents lowering the door.

If thus at any time the elevator car platform is not at any of the floors of the building and an attempt is made to open any shaft door, this is prevented as the upper end of the latch 10 prevents forcing the cross bar 8 downward. However, in many cases it is desirable that the door should be 30 opened part way to permit of reaching from the outside of the elevator shaft into the shaft for the purpose of grasping the starting rope. For this purpose the latch bar 10 is made of such length that its upper 35 end is about three or four inches, more or less, below the bottom edge of the cross bar 8 when the doors are closed. The lower door can thus be moved downward three or four inches and the upper door moved 40 upward correspondingly without interference of the latch bar 10 and this distance is sufficient to permit passing an arm from the room into the elevator shaft to grasp the starting rope, but at the same time the 45 latch bar 10 prevents opening the door any farther than about six or eight inches because if an attempt is made to depress the lower door more than three inches, its cross bar 8 encounters the upper end of the latch 50 bar 10. When the elevator car platform stops at a floor the latch bar 10 at the corresponding floor is withdrawn so as not to interfere with opening the doors completely as has been explained.

55 So far I have only described my attachment as applied on doors which are to be closed manually.

Self closing doors are locked in position when opened and this locking means for 60 locking them in open position can only op-

erate when the car platform is at the floor pertaining to the door which is to be opened as at all other times this locking mechanism does not work.

For self closing doors a beveled latch 21 70 is mounted to slide in the upper end of the lever 14. This latch at its inner end carries the pin 33. A spring 22 acts on the latch and serves to hold the same projected from the left hand edge of the lever 14. 75 When the cam 17 on the elevator car platform arrives at the head 16 and forces the same inward, the upper end of the lever 14 is forced to the left and the beveled latch 21 is brought into the path of the descending 80 bar 8 which can now be forced down as the upper end of the latch 10 has been moved to the right and out of the way. When the lower edge of the bar 8 strikes the upper beveled edge of the latch 21, it 85 forces the latch inward against the tension of its spring 22 and when the bar 8 has passed beneath the point of the latch the spring 22 forces the latch 21 outward again and over the upper edge of the bar 8 thus 90 locking the lower door in lowered position and the upper door in raised position. The doors remain in these positions but as soon as the elevator car moves up or down and the cam 17 is moved below or above the 95 head 16 on the lower end of the lever 14, the latch 21 is moved to the right whereby the bar 8 is released and is moved upward with the lower door under the action of the heavier upper door. The rising bar 8 100 presses the latch bar 10 to one side until the bar 8 is above the upper end of the latch bar 10 whereupon the latter snaps outward under the action of the spring 20 so that the upper end of the latch bar is beneath 105 the cross bar 8 and can prevent opening the doors any farther than the predetermined distances, unless the elevator car platform is on a level with the floor pertaining to said door. The length of the latch 110 bar 10 must be such that its upper end is beneath the bottom edge of the cross bar 8 when the doors are closed a distance about equal to one half of the distance that the doors are to be opened before they are automatically checked when the elevator car platform is not at the floor pertaining to 115 said door.

Having described my invention what I claim as new and desire to secure by Letters Patent is:

1. A latch for elevator doors composed of a plurality of sections completely closing a door opening and simultaneously movable in opposite directions in opening and closing 125 the door, consisting of a lever pivoted intermediate the ends thereof within the elevator shaft and having one end thereof adjacent but spaced away from the meeting line of the two door sections when closed, 130

actuating means for said lever mounted within said shaft adjacent the sill of a door opening, a spring acting to normally thrust said latch lever in the path of movement of one of said door sections and said actuating means in the path of an elevator car, an abutment on one of said door sections adapted to operatively engage said latch lever, said abutment being spaced from 5 said lever when the doors are entirely closed, and means carried by an elevator car adapted to coöperate with said actuating means and actuate said latch lever in a manner to withdraw it from the path of the door 10 whereby when no car is at a floor the doors may be opened to a limited extent only and when a car is at a floor the doors may be opened to their full extent.

2. A latch for elevator doors composed of 20 a plurality of sections completely closing a door opening and simultaneously movable in opposite directions in opening and closing the door, consisting of a lever pivoted intermediate the ends thereof within the elevator shaft and having one end thereof adjacent but spaced away from the meeting line of the two door sections when closed, an actuating lever mounted within said shaft adjacent the sill of the door opening, 25 a pivotal lost motion connection between one end of said latch lever and one end of said actuating lever, a contact member carried by the other end of said actuating lever and projecting within the elevator shaft in the path of the elevator car, a spring acting 30 upon said actuating lever whereby said contact will be normally thrust within said car and the free end of said latch lever will be normally thrust in the path of movement of one of said door sections, an abutment on one of said door sections adapted 35 to operatively engage said latch lever, said abutment being spaced from said lever when the doors are entirely closed, a spring latch member carried by said actuating lever and 40 adapted to be projected in the path of the door when in the open position and means carried by an elevator car adapted to coöperate with said contact member and actuate said actuating and said latch levers in 45 a manner to withdraw said latch lever from the path of the door whereby when no car is at a floor the doors may be opened to a limited extent only and when a car is at a floor the doors may be opened to their full 50 extent.

to a limited extent only and when a car is at a floor the doors may be opened to their full extent.

3. A latch for elevator doors composed of 55 a plurality of sections completely closing a door opening and simultaneously movable in opposite directions in opening and closing the door, consisting of a lever pivoted intermediate the ends thereof within the elevator shaft and having one end thereof adjacent but spaced away from the meeting line of the two door sections when closed, an actuating lever mounted within said shaft adjacent the sill of the door opening, a pivotal lost motion connection between one end 60 of said latch lever and one end of said actuating lever, a contact member carried by the other end of said actuating lever and projecting within the elevator shaft in the path of the elevator car, a spring acting 65 upon said actuating lever whereby said contact will be normally thrust within said car and the free end of said latch lever will be normally thrust in the path of movement of one of said door sections, an abutment 70 on one of said door sections adapted to operatively engage said latch lever, said abutment being spaced from said lever when the doors are entirely closed, a spring latch member carried by said actuating lever and 75 adapted to be projected in the path of the door when in the open position and means carried by an elevator car adapted to coöperate with said contact member and actuate said actuating and said latch levers in 80 a manner to withdraw said latch lever from the path of the door whereby when no car is at a floor the doors may be opened to a limited extent only and when a car is at a floor the doors may be opened to their full 85 extent.

Signed at New York city, borough of Brooklyn, in the county of Kings and State of New York this 23 day of February, A. D. 1915.
